UNITED STATES PATENT OFFICE

104,786

DESIGN FOR AN ADVERTISING VEHICLE

Ernest J. B. La Lumière, Cranston, R. I.

Application July 26, 1935, Serial No. 57,815

Term of patent 14 years

To all whom it may concern:

Be it known that I, Ernest J. B. La Lumière, a citizen of the United States and resident of Cranston, in the county of Providence and State of Rhode Island, have invented a new, original, and ornamental Design for an Advertising Vehicle, of which the following is a specification, reference being had to the accompanying drawing forming part thereof.

In the drawing,

Fig. 1 is a side elevation of the novel advertising vehicle;

Fig. 2 is a top plan view thereof; and

Fig. 3 is a front elevation.

I claim:

The ornamental design for an advertising vehicle, substantially as shown.

ERNEST J. B. LA LUMIÈRE.
